Attorney

UNITED STATES PATENT OFFICE.

GEORGE N. MASON, OF MOUNT PENN, PENNSYLVANIA, ASSIGNOR TO READING HARDWARE COMPANY, OF READING, PENNSYLVANIA, A CORPORATION OF PENNSYLVANIA.

FRICITION-LATCH.

1,188,805.

Specification of Letters Patent. Patented June 27, 1916.

Application filed March 23, 1916. Serial No. 86,067.

To all whom it may concern:

Be it known that I, GEORGE N. MASON, a citizen of the United States, residing at Mount Penn, in the county of Berks and State of Pennsylvania, have invented certain new and useful Improvements in Friction-Latches, of which the following is a specification.

This invention relates to improvements in friction latches and it is intended more particularly for use on a door in which it is desired to lock the door against opening through the use of the outside knob, while the inside knob action will be free to open the door.

The invention includes means for thus locking the outside knob action through the medium of key operated mechanism operable from either side of the door.

An essential feature of the invention is a means for dogging the latch bolt to prevent retracting the said latch bolt by means of a knife blade or like device inserted through the crevice between the lock and the strike plate; and in means for releasing the dogging device through the medium of the latch bolt retracting lever.

A further object is to provide a two-part knob hub, one of which parts is actuated by the outside knob, and a slide adapted to be thrown into engagement with said hub member through the medium of a lever actuated by a key and its co-acting parts.

A further object is to provide means for disengaging the dogging device from the latch bolt and to hold it in disengaged position while the door is open.

The invention is more fully described in the following specification and clearly illustrated in the accompanying drawing in which:

Figure 1 is a plan view of the latch, showing the locking slide out of engagement with the hub, both hub members being free to be operated by their respective knobs and with the dog in normal engagement with the latch bolt. Fig. 2 is a like view with the outside knob locked against latch retracting action. Fig. 3 is a detail view showing the latch bolt and the dogging device in release position. Fig. 4 is a detail view of the dog operating lever.

The numeral 1 designates the casing; 2

the spring backed latch bolt; 3 the latch retracting lever, and 4—5 the two-part hub. 55 The hub member 4 being adapted for retracting the latch bolt from the outside of the door and the member 5 for retracting it from the inside, both of which are capable of moving the retracting lever whose 60 lower extremity engaged the rear end of the latch bolt.

The numeral 6 designates a locking slide, provided with suitable guides 7 and 8 and lying in alinement with a recess 9 in the hub 65 member 4.

The numeral 10 designates a pivotally mounted lever, one end of which is bifurcated at 11 for engagement with a pin 12 on the slide 6 while its opposite end engages a lug on the slide plate 13. This plate is slidably mounted on a pin 14 on the casing and is provided with one or more tumblers 15 adapted to be operated by an ordinary door key, whereby, when the tumblers are raised the slide plate will be free to be moved in either direction.

The numeral 18 designates a friction latch provided with a spring 19 adapted to hold it normally projected and a lug 20 is formed 80 on the inner end of this latch.

The numeral 21 designates a dog, pivotally mounted on a pin 22 in the casing and provided with a spring 23 to keep its free end 24 normally in engagement with the 85 shank 25 of the latch bolt 2. This dog is formed with a depending lip 26 adapted to contact with the lug 20 on the friction latch when said friction latch is projected. On the pin 22 is also mounted a dog operating 90 lever 30, substantially S-shaped, formed with a lip 31 which lies between two lugs 32—33 on the surface of the dog 21. The elongated end 34 of this lever 30 is curved and its extremity is formed with a depression 35 adapted for engagement by a lug 36 on the free end of the latch retracting lever 3.

With the parts in the position shown in Fig. 1, the latch bolt may be retracted and the door opened by turning the knob on either side of the door. When it is desired to lock the latch bolt against retraction by the outside knob action, the key is inserted and the slide plate thrown to the front of 100 the casing, that is, to the position shown in

Fig. 2. This action will, through the medium of the pivoted lever 10, throw the end of the locking slide 6 into the recess 9 of the hub member 4 and lock that member 5 against turning, which will effectually prevent opening the door from the outside by the knob action, while the inside knob action will be free to retract the latch bolt, as shown in Figs. 2 and 3.

10 It is evident that the locking slide may be thrown into or out of engagement with the hub member 4 by the key actuated mechanism from either side of the door.

When the outside knob action is not 15 locked, the turning of either knob will move the lever 3 and the lug 36 will depress the elongated end of the lever 30 and cause the lip 31 on its opposite end to bear against the lug 32 and thus raise the free end 24 of the dog free from engagement with the latch bolt 2, and the continued movement of the lever 3 will retract the latch bolt.

When the outside knob action is locked, through the key operated mechanism above 25 described, the outside knob cannot turn but the inside knob will be free to turn the hub member 5 and this will actuate the lever 3, releasing the dog through the lever 30, and permit the latch bolt to be retracted.

30 Figs. 1 and 2 show the parts in position with the door closed, and the numeral 40 designates the strike plate. In this position the friction latch 18 contacts with the strike plate and its lug 20 is kept free from contact 35 with the lip 26 on the dog, but, when the door is open the spring 19 will project the latch 18 and the lug 20 will press forward on the lip 26 and raise the free end 24 of the dog from its engagement with the latch 2, 40 so that it will be free to move when the door is in the act of closing, and this closing of the door will force the latch 18 to its innermost position, as shown, and allow the end 24 of the dog to again engage the latch bolt.

45 The latch shown is reversible, in that it may be applied to doors operating in both directions by merely reversing the latch bolt so that it will contact with its tapered surface on the lock strike, and to facilitate this 50 easy reversal, the projecting end of the friction latch may be rounded if desired.

Having thus fully described my invention, I claim:—

1. In a latch, a casing, a spring backed 55 latch bolt, a retracting lever for the latch bolt, a lug on the free end of said lever, a two-part hub adapted to actuate said lever, one hub member being operable from the outside and the other from the inside of the 60 door, a horizontally movable locking slide adapted to be moved into engagement with the outside operating hub member, a pin on said slide, a lever pivoted to the casing and having a bifurcated end engaging the pin, a 65 slide plate in engagement with the opposite

end of said lever and key actuated means for moving said slide plate, whereby the turning of the key from either side of the door will lock the latch bolt against retraction from the outside, a dog pivotally mounted in the 70 casing whose free end normally engages the latch bolt, a lug on the dog, a lever mounted on the same pivot with the dog, a lip on said lever for engagement with the lug on the dog, the opposite end of the lever having a 75 depression for engagement with the lug on the retracting lever, whereby the operation of the retracting lever will release the dog from its engagement with the latch bolt.

2. In a latch, a latch bolt, a retracting lever for the bolt, a two-part hub of which one member is operable from the outside, and key operated means for locking said bolt against retraction by the outside knob action comprising a slide adapted to engage 80 one of said hub members and a pivoted lever, one end of which engages the slide and the other end the key operated mechanism, in combination with a dog pivotally mounted in the casing and whose free end 85 normally engages the latch bolt, a lug on said dog, an operating lever for the dog, a lip on said operating lever adapted to engage the lug on the dog, the opposite end of 90 said lever being in engagement with the latch bolt retracting lever, whereby the actuation of the retracting lever will disengage 95 the dog from the latch bolt.

3. In a latch the combination of a latch bolt, a retracting lever therefor, a two-part hub, one of which is operable from the outside and the other from the inside, a locking slide for the outside hub member, key actuated mechanism for operating the slide, a pivoted dog adapted to normally hold the latch bolt projected, an S-shaped lever pivotally mounted in the casing, one end of 100 which is engaged by the retracting lever and the other end with the dog, whereby, when the outside hub member is locked the inside hub member may actuate the retracting lever and through the medium of the S-shaped lever release the latch bolt from the dog, and a spring backed friction latch adapted to hold the dog free from engagement with the 105 latch bolt when the door is open.

4. In a latch bolt dogging mechanism a pivotally mounted dog, a spring to hold the dog normally in engagement with the latch bolt said dog having a lug thereon, an S-shaped dog operating lever mounted on the pivot with the dog, said lever having a lip at one end for engagement with the lug on the dog and an elongated opposite end formed with a depression, a latch retracting lever formed with a lug adapted to engage the depression in the lever, and a friction latch adapted to hold the dog free from contact with the latch bolt when the friction latch is in projected position.

5. A dogging device for a latch bolt provided with a retracting lever, comprising a dog, means for holding the dog normally in engagement with the latch bolt, a pivotally mounted dog operating lever, a lip on said lever adapted for engagement by the dog, the opposite end of the lever having a de-

pression adapted for engagement by the latch retracting lever, and a friction latch adapted to hold the dog free from contact 10 with the latch bolt when the friction latch is in projected position.

In testimony whereof I affix my signature.
GEORGE N. MASON.
